ATTORNEY.

UNITED STATES PATENT OFFICE.

JOSEPH CORBE, OF WASHINGTON, DISTRICT OF COLUMBIA, ASSIGNOR TO ROBERT HENRY SIMPERS, OF WASHINGTON, DISTRICT OF COLUMBIA.

ILLUMINATING DEVICE FOR SEWING MACHINES.

1,419,822.

Specification of Letters Patent. Patented June 13, 1922.

Application filed November 22, 1921. Serial No. 516,977.

To all whom it may concern:

Be it known that I, JOSEPH CORBE, a subject of the King of Italy, residing at Washington, District of Columbia, have invented 5 certain new and useful Improvements in Illuminating Devices for Sewing Machines, of which the following is a specification.

This invention appertains to certain improvements in electric lamps generally, and 10 more particularly to a portable type of the same adapted to be easily and readily mounted in position on sewing machines or the like for the purpose of illuminating the work done thereon, and to otherwise facilitate the threading of the sewing needle 15 thereof and the manipulation of the presser foot mechanism for the proper positioning of the work with respect thereto for accurate sewing operations.

20 The principal object of the invention is to provide for a lamp support of the class mentioned and one wherein the lamp carried by the same is readily swung in one direction to a position as to not in anyway interfere with the ordinary operation of a 25 sewing machine, when the lamp is not in use, and in another direction whereby the lamp is automatically lighted simultaneously with the final movement of the same 30 to desired operative position, when the lamp will be disposed in close proximity to the presser foot and needle mechanism of the machine and to the work being acted upon thereby.

35 Another object of the invention is to provide for an electric lamp of the type set forth, and one of an extremely simplified and inexpensive construction and arrangement, durable and efficient in operation, and 40 which is capable of being easily and readily mounted in or displaced from operative position.

A further object of the invention is to 45 provide for a portable electric lamp of the character mentioned, and one embodying an extremely simple form of clamping means whereby the lamp may be conveniently supported for swinging movements to and from operative position, and a similar form of 50 switching means whereby the lamp is automatically connected in circuit with a suitable source of current supply when the lamp is swung to its operative position.

With the foregoing and other objects in 55 view, the invention resides in the certain

novel and useful construction and arrangement of parts as will be hereinafter more fully described, set forth in the appended claim, and illustrated in the accompanying drawing, in which:—

Figure 1 is a front elevation of the head of a sewing machine of conventional form, and showing a preferred embodiment of the electric lamp as applied thereto and in its operative position thereon,

Fig. 2 is a longitudinal section taken on the line 2—2 of Fig. 1, and,

Fig. 3 is a fragmentary perspective view of the clamp and switching portions of the lamp per se.

Referring to the drawing, the numeral 10 designates a resilient clamping element formed of a strip of spring metal, such as steel or the like, of a suitable length to be shaped to substantially circular form with 75 its opposite ends spaced apart for a short distance, one end from the other, and slightly outturned, as at 11, in a manner to facilitate the engaging of the clamp as a whole around an object in the well known 80 manner of such devices. Secured on the outer surface of the medial portion of the clamp 10 is a disk of metal such as brass 12, which has its inner face shaped to conform to the curvature of said surface, and its 85 outer face flat and tangent to the latter. Mounted on the outer flat face of this disk 12 is the circular end portion 13 of a supporting arm 14, of an insulating material, and the circular portion of which is of equal 90 diameter to that of the disk 12, the arm 14 and the disk 12 being secured in position on the clamp 10 by means of a single screw 15, which is passed centrally through the circular portion 13 of the arm 14, and the disk 12, 95 and threaded into engagement with a complementary threaded opening formed in the said medial portion of the clamp 10 for such purpose. Secured to the free end of the arm 14, is an extension arm 16, which has 100 its connected end cutaway to form a recessed portion for the seating therein of the end of the arm 14, and these parts are secured together, one in alignment with the other, by means of rivets, screws or the like. 17. 105 This extension arm 16 is formed of insulating material and has a bore 18 extending longitudinally thereof from a point inwardly from its recessed connected end portion and opens outwardly of its free end and 110

into the bore of a lamp socket member or sleeve 19, which is fitted over the free end of the arm 16, substantially as shown.

- The lamp socket member or sleeve 19 is formed of an insulating material, corresponding to that of the extension arm 18 and the arm 14, and has fitted into the outer end of its bore, beyond the connected end of the extension arm 16, a threaded metal socket 20 for the screwing therein of the usual threaded base of an electric lamp 21, the latter being preferably provided with a reflector 22, whereby the light rays from the same are concentrated and projected forwardly from the end of the bracket arm formed by the arm portion 14 and the extension arm 16. The usual center contact of the base of the lamp 21 engages with the free end of a resilient contact finger 23, when the lamp is screwed inwardly of the metal socket 20, and this finger 23 is secured in position within the outer end of the bore 18, of the extension arm 16, by means of a screw 24, which is threaded into position so as to not only retain the contact finger 23 in place, but also serves to secure the lamp socket member or sleeve 19 on the arm 16, substantially as shown. The contact finger 23 is electrically connected to one end of a conductor 25, which is passed rearwardly through the bore 18, of the extension arm 16, and outwardly of an opening 26 in the wall thereof, and from thence leads to and connects at its other end a contact segment or strip 27, which is secured on the circular portion 13, of the arm 14, by means of a screw or the like 28. This contact segment or strip 28 is disposed adjacent to the periphery of the circular portion 13, so that, when the bracket arm is swung on the screw 15 as its pivot, it will be moved into contact with a resilient contact finger 29 curved over the peripheral edge of the circular portion 13 from its point of support on a screw 30 secured in the peripheral edge of the disk 12 on the clamp member 10.

Similarly, the metal lamp socket 20 in the bore of the socket sleeve 19, carried at the outer end of the arm extension 16, is electrically connected to one end of a conductor 31, which passes rearwardly therefrom in the bore 18 of the latter, and connects at its other end a binding post 32 secured in the wall of the bore 18 adjacent the inner closed end thereof. A battery 33 is now connected, by means of a conductor 34, to the screw 31 of the contact finger 29, and, by means of a conductor 35, to the binding post 32 carried by the arm extension 16, when, upon swinging the bracket arm formed by the arms 14 and 16 on its pivot screw 15, the contact segment or strip 27 frictionally engages under the contact finger 29, when the circuit from the battery 33 will be closed to the lamp 21.

In the particular adaptation of the lamp thus provided, and as shown in Fig. 1, the clamp member 10 is to be snapped over the arm *a* of a sewing machine head, and when the lamp is not in use, the bracket arm thereof is swung upwardly to a position to lie in close parallel relation with respect to the arm *a*, where it will in no way interfere with the ordinary operations of the machine. Now, with the conductors 34 and 35 leading from the battery 33 and connecting the screw 30, of the contact finger 29, and the binding post 32, respectively, and it is desired to make use of the light from the lamp 21 on the work during the operation of the machine, or to facilitate the threading of the needle of the latter, when the machine is inoperative, the bracket arm of the lamp 21 is swung downwardly on its pivot 15, and, when properly positioned to have the deflector 22 throw the beam of light from the lamp directly onto the presser foot and needle portions of the sewing mechanism, the contact segment or strip 27 will frictionally engage under the resilient contact finger 29, whereby the circuit is closed to the battery 33 and the lamp 21 will be lighted, the frictional contact between the contact segment or strip 27 and the contact finger 29 being sufficient to maintain the bracket arm in such operative position as long as it is desired to illuminate the working point of the machine.

From the foregoing, it will be noted that in applying the lamp as a whole for use in the manner indicated for the same and on a sewing machine, the contact finger 29 and the contact segment or strip 27 must be properly positioned one with respect to the other so as to effect the closing of the circuit between the battery 33 and the lamp 21 only during the final movement of the bracket arm carrying the lamp to the desired operative position, whereby the light beam from the latter is directed onto the work at the exact point of the sewing operation, and so that the said contacts 27 and 29 will remain in frictional engagement to hold the arm and the lamp in such position.

It is to be well understood that, while a preferred embodiment of the lamp and its supporting and switching means have been described and illustrated herein in specific terms and details of construction, arrangement and operation, various changes in and modifications of the same may be resorted to without departing from the spirit of the invention, or the scope of the claim appended hereto.

Having thus fully described the invention, what is claimed, is:—

In a support for electric lamps, the combination of a clamping means, a disk of an insulating material carried by said clamping means, a second disk of insulating ma-

- terial pivotally mounted on said first mentioned disk, and of equal diameter with respect thereto, an arm formed with said second disk and extending radially therefrom, an arm extension secured to said arm in alignment therewith, an electric lamp socket carried at the free end of said arm extension and having a lamp seated therein, a switching means having a contact finger 5 fixed in position on the peripheral edge of said first mentioned disk, and projecting over the peripheral edge of said second mentioned disk, and a second contact carried by the latter disk and cooperating with said contact finger, and electrical connections 15 connecting said lamp socket with the contact finger and contact of said switching means.
- 10 In testimony whereof I affix my signature hereto.

JOSEPH CORBE.
